UNITED STATES PATENT OFFICE

152,496

DESIGN FOR A ROAD SIGNAL OR THE LIKE

Hyman A. Premack, Chicago, Ill.

Application December 19, 1946, Serial No. 135,609

Term of patent 3½ years

(Cl. D72—1)

To all whom it may concern:

Be it known that I, Hyman A. Premack, a citizen of the United States of America, residing at Chicago, in the county of Cook and State of Illinois, have invented a new, original, and ornamental Design for Road Signals or the like, of which the following is a specification, reference being had to the accompanying drawing, forming part thereof.

Fig. 1 is a front view of a road signal or the like, showing my new design.

Fig. 2 is a side view with leg of stand partially broken away.

Fig. 3 is a top plan view in reduced scale.

I claim:

The ornamental design for a road signal or the like, as shown.

HYMAN A. PREMACK.
